UNITED STATES PATENT OFFICE.

HANS RIEGGER, OF BERLIN-PANKOW, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

FILTER CHAIN.

Application filed August 8, 1922, Serial No. 580,470, and in Germany August 31, 1921.

It is generally known that currents of a predetermined frequency can be separated from currents of different frequencies by using an electric oscillatory circuit which is 5 tuned to the desired frequency. It responds to the desired frequency while all other frequencies are more or less strongly suppressed. If several of such oscillatory circuits are connected in series, the deviating 10 frequencies will disappear more and more with every consecutive circuit and the desired frequency will be more and more emphasized. Such electric oscillatory circuits connected in series are known in the art as 15 filter chains.

Filter chains are used in connection with wireless telegraphy and telephony and further with high frequency line telegraphy and telephony. When thus applied, it is, 20 however, not sufficient to make the system responsive strictly to one single frequency as the sending frequency cannot always be maintained accurately. The filter chains should, if they are to answer these purposes, 25 rather permit the passage of several frequencies within a predetermined frequency range. When using a single oscillatory circuit, this can be attained by a somewhat stronger damping; the greater the damping 30 the flatter will be the resonance curve.

In order that the invention may be clearly understood, I shall proceed to describe the same with reference to the accompanying drawings, in which:

35 Fig. 1 shows a resonance curve of the simplest form, characteristic of a damped circuit;

Fig. 2 shows an ideal resonance curve of rectangular form;

40 Fig. 3 shows the resonance curve of a five-link filter chain;

Fig. 4 shows the resonance curves of a chain with two oscillatory circuits and of a chain with three oscillatory circuits;

45 Fig. 5 shows the curve produced by the chain of five links;

Fig. 6 represents a circuit diagram of a five-link chain referred to in Fig. 5;

Fig. 7 shows the damping curve and the 50 damping and coupling curve of a chain, one part of which consists of one link and the other part of two links;

Fig. 8 is a diagram of a resonance curve

produced by the superposition of the two curves in Fig. 7;

55 Fig. 9 shows the resonance curves of the different parts of an improved filter chain; and

Fig. 10 shows the resonance curve of the 60 entire chain.

In Fig. 1, I designates the resonance curve at smaller damping and II the resonance curve at greater damping. As abscissae the frequencies, and as ordinates the amplitudes of current, are plotted. The oscillatory circuit is tuned to the period of vibrations ω_1 . The requirement is that the frequencies within the range $\omega' - \omega''$ should 65 freely pass through the circuit, but that frequencies below or above that range should 70 be excluded. The figure shows that an oscillatory circuit with the resonance curve II produced by increased damping is not a satisfactory expedient. For, it will be observed that those frequencies which correspond 75 exactly to the desired frequency are considerably reduced in oscillation amplitude, whereas the undesired frequencies are not sufficiently suppressed. The ideal would be a resonance curve of rectangular form 80 as shewn in Fig. 2. With this curve, all frequencies between ω' and ω'' would be transmitted equally well, but all other frequencies would be almost entirely suppressed.

85 While, of course, a resonance curve of this exact rectangular form would be very difficult to obtain, the means proposed by the present invention result in a resonance curve, very closely approximating this ideal form. 90

If filter chains are used, the frequency range to be transmitted can be enlarged by providing a close coupling of the individual oscillatory circuits. In this case, complex resonance curves of the coupled circuits will 95 be obtained, the peaks of which are the farther distant from each other the closer the coupling is. Fig. 3 shows the resonance curve of a five-link filter chain and shows that this curve is already much more similar 100 to the rectangular curve shown in Fig. 2 than the resonance curve II of Fig. 1. By varying the tuning, the damping of a highly damped circuit, and the degree of coupling of the different links of the filter 105 chain, the shape of the resonance curve can

be altered, and it might even be possible to produce, by experiments, filter chains which in a satisfactory manner come close to the ideal form of Fig. 2. Such experiments require, however, much time and are not very reliable, as they do not give any guarantee of attaining the best that can be realized with the means at disposal.

The present invention relates to a special kind of filter chain, in which, by calculation or by designing, a favourable form of the resonance curve can be produced. The fact that the tuning frequencies, the damping, and the degrees of coupling, required for this purpose, can be determined before this chain is constructed, constitutes an important improvement over the filter chains known at present.

The filter chains, according to the present invention, are characterized by the feature that the degree of coupling between two of their links is so loose that between these two links no noticeable effect of coupling resonance is produced, while the coupling between all other links is closer, e. g. so close that distinct coupling resonance points are produced. The loose coupling point separates thus the chain into two parts, each part by itself possessing its individual resonance curve. Each of the two curves shows a number of peaks which are the more pronounced the closer the coupling is between the individual links of the corresponding part of the chain. The greater the damping is made at the same degree of coupling, the closer will the peaks come together. The number of and the distance between the peaks can be determined by calculation. The calculation becomes specially simple if each part per se of the chain is made homogenous, e. g. if all the links of the corresponding part of the chain are tuned to the same frequency and have the same damping and if the different links possess the same degree of coupling. Even if the decrements do not agree, a common average decrement can be used for the calculation, provided, of course, that the number of links is not too large. By loose coupling of the two parts of the chain, a resonance curve is obtained which resembles very nearly the rectangular curve, provided the peaks and the valleys of each part are selected in such a manner that the peaks of one resonance curve are located between the peaks of the other resonance curve. This can be carried out in a particularly easy manner if one part of the chain has an even number of links and the other part an odd number of links. In this case, a valley will occur at the middle of the first chain part and a peak at the middle of the other chain part. If, further, care is taken that the peaks of one curve coincide with the valleys of the other curve, a curve is pro-

duced such as is shown for instance in Fig. 5. This curve results from the superposition of the two resonance curves III and IV of Fig. 4. III is the resonance curve of a chain with two oscillatory circuits, and IV that of a chain with three oscillatory circuits. The circuits are diagrammatically shown in Fig. 6. The first part of the chain consists of the oscillatory circuits 1 and 2 which are closely coupled with each other and excited by the windings 6. The second part of the chain consists of the oscillatory circuits 3, 4, 5. The fifth oscillatory circuit 5 transmits the energy to the windings 7 which conduct the same to any receiving device desired. The coupling between 1 and 2 is so close that a distinct two peak curve is produced such as shown at III in Fig. 4. The oscillatory circuits 3, 4, 5 are also coupled with each other so closely that the effect of the coupling resonance is distinctly perceivable (curve IV, Fig. 4), although the formation of several peaks has not yet been attained. If now the first part of the chain and the second part are coupled with each other by loosely coupling the oscillatory circuits 2 and 3, the curves III and IV will coincide. In order to find out, as function of the frequency, those current amplitudes which at constant excitation are transmitted from the windings 6 to the windings 7, it is merely necessary to multiply with each other similar values of the curves III and IV. The result will be the resonance curve shown in Fig. 5 of the entire chain consisting of five links. This curve comes already very near the rectangular shape. The slight fluctuations in the horizontal part of the curve between c and d are not at all disturbing so that oscillations of all frequencies which are situated between these two frequencies c and d , pass equally freely through the chain. In front of point c and behind point d the curve drops everywhere quite steeply.

Owing to the ease with which the curve in Fig. 5 can be calculated from the curves III and IV (by multiplication of the corresponding values of III and IV), it is not difficult to select, in designing, those forms of the curves III and IV which together result in the most favourable compound curve. The forms for the curves III and IV on the other hand can easily be varied, as mentioned above, by altering the damping and the coupling degrees.

The advantages of the invention become already obvious if one part of the chain consist of one link only and the other part of the chain of two links. If the damping for one link is so selected that the curve V of Fig. 7 is produced, and if the damping and the coupling degree of the two links of the other part are so selected that the resonance curve VI is produced, both curves together will result in a resonance curve as shown in

Fig. 8, which, obviously, is a really very favourable curve for practical purposes.

The resonance curve for the entire chain can be found from the resonance curves of its parts by a simple multiplication of the corresponding values, but only if the coupling between the two parts is loose. If by experiments, during the design, the most favourable relations for the damping and coupling degrees between the links of the individual parts have once been determined, it will frequently be possible to further improve the form of the curve by a slight increase in the coupling factor between the two parts. Fig. 9 shows the resonance curves VII and VIII of the individual parts of a chain by the superposition of which portions the resonance curve of the entire chain shown in Fig. 10 is produced. The curve portion of Fig. 10 drawn in full lines is the resonance curve with loose coupling between the two parts of the chain. The figure shows that the two lateral peaks *e* and *f* are considerably higher than the middle peak *g*. If the damping and coupling for the individual parts of the chain have been determined in such a manner that the full line curve shown in Fig. 10 is produced, the peaks *e* and *f* can now also be lowered so far that they do not much exceed the peak *g*, as is shown in dotted lines in Fig. 10. This result is attained by somewhat closer coupling between the two parts of the chain. If this coupling is selected sufficiently close, the effect of coupling resonance will just be noticeable, the peaks of the curve in Fig. 10 being then no longer simple products from the curves VII and VIII of Fig. 9, but in this case a complicated calculation takes the place of a simple multiplication. Anyhow, one or at the utmost two experiments will be sufficient to ascertain that degree of coupling, which brings the three peaks *e*, *f*, *g* approximately to the same height. The coupling degree between the two parts of the chain must, however, still be smaller than the coupling degrees between the links of each individual part, as otherwise the less perfect curve of an ordinary five-link chain as shown in Fig. 3 would be produced.

It is obvious to any skilled person that a third chain part could be added by loose coupling to a chain composed of two loosely coupled parts in order to still closer approximate the rectangular form by superposition of a third resonance curve.

What I claim, is:

1. Filter chain for transmitting oscillations within a limited range of frequencies, comprising at least two coupled groups of oscillatory circuits, at least one of said groups comprising at least two adjacent oscillatory circuits, coupled with each other sufficiently close to produce a resonance curve of that group having at least two peaks, the resonance peaks of one group of circuits occurring at frequencies different from those at which the peaks of the other group occur. 60 65

2. Filter chain for transmitting oscillations within a limited range of frequencies, comprising at least two coupled groups of oscillatory circuits, at least one of said groups comprising at least two adjacent oscillatory circuits, coupled with each other sufficiently close to produce a resonance curve of that group having at least two peaks, the resonance peaks of one group of circuits coinciding with the resonance valleys of the other group. 70 75

3. Filter chain for transmitting oscillations within a limited range of frequencies, comprising at least two coupled groups of oscillatory circuits, at least one of said groups comprising at least two adjacent oscillatory circuits, coupled with each other sufficiently close to produce a resonance curve of that group having at least two peaks, one of said groups having an even number and the other group having an odd number of oscillatory circuits. 80 85 90

4. A filter chain for transmitting oscillations within a limited range of frequencies comprising at least two groups of oscillatory circuits, each of said two groups comprising at least two adjacent oscillatory circuits coupled with each other sufficiently close to produce a resonance curve for the respective group having at least two peaks, and means for loosely coupling said groups with each other. 95 100

5. A filter chain according to claim 4 in which the resonance peaks of one group of circuits occur at frequencies different from those at which the peaks of the other group occur. 105

6. A filter chain according to claim 4 in which the resonance peaks of one group of circuits substantially coincide with the resonance valleys of the other group. 110

7. A filter chain according to claim 4 in which the circuits comprising each group are tuned to the same frequency.

In testimony whereof I affix my signature.
HANS RIEGGER.
